UNITED STATES PATENT OFFICE.

WILHELM KNOPFF, OF BERLIN, GERMANY.

INCUBATOR.

SPECIFICATION forming part of Letters Patent No. 404,634, dated June 4, 1889.

Application filed January 8, 1887. Serial No. 223,801. (No model.)

To all whom it may concern:

Be it known that I, WILHELM KNOPFF, of Berlin, in the Kingdom of Prussia and German Empire, have invented new and useful 5 Improvements in Incubators, of which the following is a specification.

The object of this invention is to imitate as closely as possible the effect of a setting hen on the eggs which she covers.

10 To this end my invention consists in the construction and combination of parts hereinafter set forth and claimed.

In the accompanying drawings, Figure 1 represents a front elevation of my incubator; 15 Fig. 2, a horizontal section of the same on the line A B of Fig. 1; Fig. 3, a vertical section on the line C D of Fig. 2; Fig. 4, a similar section on the line E F of Fig. 2; Fig. 5, a plan view of the evaporating-box. Figs. 6, 7, 8, 20 and 9 are detail views of the devices for raising and lowering the artificial mother, Figs. 6 and 7 being elevations taken at right angles to each other, Fig. 8 illustrating a modified arrangement of the upper rods, and Fig. 9 representing a plan view.

A designates the casing of the incubator, having a base B, roof C, and door b². Within this casing are rectangular double walls b b', leaving a water-space a between them, and 30 closed at the top and bottom, so as to form a water-jacket. This is complete on all sides, except at the front, where a door b² gives access to the space within said water-jacket. In the lower part of this space an evaporator-drawer e, provided with small water-pockets e' of any convenient number, is supported on guideways or shelves f', formed in said water-jacket. The said drawer extends through the front of the incubator A, so that it may be 40 drawn in or out at will.

Between the base B and the bottom plate y³ of the casing a gas-burner j is arranged. The heat from this burner evaporates the water in pockets e'. The evaporation is accelerated by 45 a draft of air through valves s', which open at the front of the incubator into the space immediately below said evaporator-drawer. Corresponding valves s, similarly arranged in the upper part of the front of casing A, allow 50 exit to said draft. The said valves s s' are hinged to the casing, so that either of them may be entirely opened at will. Valve s is

also provided with apertures u, and valve s' with apertures u', through which a lesser draft of air will normally pass, even when the valves s s' are closed, as shown in Fig. 1. Immediately above said evaporator-drawer a nest-drawer d is arranged, having several compartments and perforated walls and bottom. Each compartment is provided with soft 60 fibrous material shaped to form a nest and having filaments which dangle into the water in pockets e', in order that capillary attraction may supply the nests with sufficient moisture to aid in keeping the under side of 65 the eggs moderately cool. The steam from the evaporating-drawer also ascends through the bottom perforations of this nest-drawer and aids in the same cooling and moistening operation. Air enters said nest-drawer 70 through these holes, and also through the holes d² in its side walls. The nest-drawer is supported on shelves or guideways f, formed in the water-jacket, and may be withdrawn through the door b².

Immediately above the nest-drawer an artificial mother c is suspended, consisting of a hot-water receptacle having rubber bellies c' extending downward, one to each nest. The curvature of the nest corresponds to that of 80 the bellies, and consequently each egg is in contact with a belly of the artificial mother when the latter is lowered for hatching. The hot water is supplied to said receptacle or artificial mother through flexible pipes h, Figs. 1, 85 3, and 4. The said artificial mother is raised and lowered by a hand-wheel w', which turns a screw-shaft w⁴, so as to make a nut w⁵ travel up or down thereon according to the direction of rotation. This nut is connected by levers 90 w⁵, w⁶, and w⁷ to the top of the receptacle or artificial mother aforesaid.

The water-space a is supplied with fresh water from a receptacle k through a pipe m and angular tube m'.

A thermometer r is arranged in a small casing, which communicates with the interior of the receptacle or artificial mother c, and another thermometer r is similarly arranged in a receptacle communicating with the water-space a. The heat of the water in the said receptacle and in the water-jacket is indicated by these thermometers through windows left in their casings.

The space under roof C is used as a coop for the young chickens, and is preferably extended laterally by wing D.

Having thus described my invention, what I claim as new, and desire to secure by Letters Patent, is—

A series of nests and the box or drawer containing them, in combination with a hot-water receptacle or artificial mother arranged for contact with said eggs, and a screw-shaft,

nut, and levers for raising and lowering said artificial mother at will, substantially as set forth.

In witness whereof I have hereunto set my hand in presence of two witnesses.

WILHELM KNOPFF.
